UNITED STATES PATENT OFFICE.

ARTHUR R. MUTTON, OF WATERLOO, IOWA.

DESIGN FOR A SUIT OF PLAYING-CARDS.

45,781.

Specification for Design.

Patented May 12, 1914.

Application filed February 5, 1914. Serial No. 816,851. Term of patent 7 years.

To all whom it may concern:

Be it known that I, ARTHUR R. MUTTON, a citizen of the United States of America, and a resident of Waterloo, Blackhawk county, Iowa, have invented a new, original, and ornamental Design in Suits of Playing-Cards, of which the following is a specification, reference being had to the accompanying drawing, forming part hereof.

The drawing is a plan view of a suit of playing cards illustrating my new design.

I claim:

The ornamental design for a suit of playing cards, as shown.

Signed at Waterloo, Iowa, this 20th day of Jan. 1914.

ARTHUR R. MUTTON.

Witnesses:

W. H. BRUNN,
GEO. C. KENNEDY.
